The ornamental design for a stackable drawer with a stand, as shown and described.

DESCRIPTION

FIG. 1 is a perspective view of a stackable drawer with a stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of an indicated portion of FIG. 1;

FIG. 9 is another perspective view of an additional arrangement of stackable drawer and a stand, drawn in broken lines;

FIG. 10 is another right side view of the additional arrangement of stackable drawer and the stand, drawn in broken lines; and,

FIG. 11 is another enlarged view of an indicated portion of FIG. 10, showing that one corner of the stand is fixed with the stackable drawer by a fastener of the stand, and another corner is not fixed by the fastener.

The broken lines of the additional arrangement of the stackable drawer and the stand in FIGS. 9-11 illustrate unclaimed environment and forms no part of the claimed design.
